LATCHING DEVICE

Edward M. Kealy, Long Beach, Calif.

Application August 11, 1945, Serial No. 610,377

7 Claims. (Cl. 292—6)

(Granted under the act of March 3, 1883, as amended April 30, 1928; 370 O. G. 757)

1

This invention relates to latching devices and more particularly to latch actuating means.

Objects of my invention are to provide an improved latch actuating device for simultaneously actuating a plurality of latch bolts by the manipulation of a single operative means; to provide improved actuating means for translating reciprocal motion into a gyrate motion; to accomplish the noted objects in a facile, economical, and efficient manner; and to provide improved elements and arrangements thereof in a device of the character and for the purposes set forth.

In accomplishing these and other objects of the present invention, I have provided improved details of structure, the preferred form of which is shown in the accompanying drawing, wherein:

Fig. 1 is an exploded view of the actuating device.

Fig. 2 is a plan view of a device embodying the features of the present invention, associated with a latch and mounted on a closure member.

Fig. 3 is a front elevation of the actuating device, showing in full lines the parts thereof in latching position, and in dotted lines the unlatch positions of the swivel pin and latch bolts.

Referring more in detail to the drawing:

In Fig. 1, the number 1 indicates a substantially rectangular flat plate or base of metal or other suitable material having small apertures 2 in its end portions and an enlarged circular opening 3 intermediate the apertures.

Side portions or flanges 4 are disposed substantially perpendicular to the base 1 on each side of the opening 3 so as to provide a substantially U-shaped or channel portion. The side portions 4 have cam ways 5 formed therein consisting of elongated openings or slots canted equally and oppositely from a plane transverse to the base 1 and passing through the axis of the circular opening 3.

A cylindrical push button or element 6 slidably engages within the opening 3 of the base or plate and has a coaxial cylindrical extension 7 of reduced diameter formed on its inner end.

A swivel pin or gyrate member 8, having a central opening 9 and apertures 10 formed in its ends, is positioned in, and controllably engaged by, the cam ways 5.

The swivel pin 8 is secured to the push button 6 by the extension 7 engaging within the opening 9 and having its extremity upset or enlarged. So mounted, the swivel pin 8 pivots on the push button 6 and is directed in gyrate motion by

2

the cam ways 5 in response to reciprocal motion of the push button.

A flat spring member 11 bears against the upset extremity of the extension 7 to resist inward movement of the push button 6 and the swivel pin 8. Suitable screws 12 are adapted to extend through the apertures 2 and receive nuts 13 for fastening the base to the closure 14, as shown in Fig. 2, and to secure the spring 11 to said base.

In Fig. 2, an exemplary mounting of the device is shown secured to the closure 14 by the mounting screws 12 and nuts 13 in an arrangement for actuating latch bolts 15.

Referring to Fig. 2 and to Fig. 3, the latch bolts 15 terminate at their inner ends in yoke portions 16, which are cooperatively connected to the outer end portions of the swivel pin 8 by suitable keys 17 engaging within the apertures 10.

The latch bolts 15 extend beyond the closure 14 and have bevelled ends 18 engaging latch keepers 19 of substantially conventional design.

If desired the outer end portions of the swivel pin 8 may be arranged to engage suitable keepers 20, as shown in dotted lines in Fig. 3, in addition to the engagement of the bolts 15 with the keepers 19. Of course, the bolts 15 may be eliminated when the swivel pin 8 functions as a latch.

Operation

The operation of the latch device constructed as described is as follows:

To release the latch when the closure 14 is in place, external pressure is applied to the push button 6 thrusting it inwardly against the resisting pressure of the spring 11.

As the push button 6 moves inwardly, the swivel pin 8 mounted thereon is directed in a gyrate path by the cam ways 5.

The arcuate movement of the ends of the swivel pin 8 retracts the latch bolts 15, to disengage the keepers 19 and release the closure.

To relatch the closure 14, the same is returned to place, the latch bolts 15 being automatically retracted by the action of the bevelled ends 18 and so maintained until reengaged with their keepers by the outward pressure of the spring member 11.

The operation of the latch bolts 15 as described is an exemplary use of the actuating device of this invention. In addition, however, latch keepers 20 may be provided as shown in Fig. 3 to engage the ends of the swivel pin 8 to provide an additional or alternate latching arrangement.

While I have shown but one embodiment of my invention, it is apparent that the device is susceptible to modification without departing from the spirit of the invention. I do not wish, therefore, to be limited by the disclosures set forth, but only by the scope of the appended claims.

The invention described herein may be manufactured and used by or for the Government of the United States of America for governmental purposes without the payment of any royalties thereon or therefor.

I claim:

1. A latch comprising a base member having an opening formed therein, two side elements supported substantially at right angles to the base member having formed therein a pair of juxtaposed cam slots consisting of elongated openings equally and oppositely canted from a plane vertical to the base member and formed in spaced relation to the opening, a cylindrical push button element slidably engaged within the opening of the base member and having a coaxially formed cylindrical extension of reduced diameter, a swivel pin member pivotally supported near its midpoint on the push button extension and extended through the cam slots so as to be directed thereby and have its end portions moved through arcuate paths in response to reciprocal movement of the push button element, a spring member mounted on the base member and positioned to bear against the extension of the push button element and resist inward longitudinal movement thereof, and latch bolts pivotally connected to the end portions of the swivel pin, the ends of said latch bolts and swivel pin being adapted to engage latch keepers.

2. In a latch of the character described, a base member having mounting openings and push button receiving opening formed therein, side elements supported substantially perpendicular thereto having cam slots formed therein, a push button positioned in the opening, a swivel pin pivotally mounted on the inner end of the push button, and extended through the cam slots so as to be directed thereby to cause its outer ends to describe spiral paths in response to push button movement, a spring supported by the base member in a position resistive to the inward motion of the push button, and latch bolts pivotally secured to the extended end portions of the swivel pin and actuated thereby in the engaging and disengaging of latch keepers.

3. A latch comprising a channel shaped base member having an opening formed in its bottom, the sides of the channel shaped base member having juxtaposed cam slots consisting of elongated openings equally and oppositely canted from a plane perpendicular to the base member, a swivel pin positioned in the cam slots, a push button positioned in the opening to actuate the swivel pin, a spring supported by the base member to resist inward movement of the push button, and

latch bolt members cooperatively engaged and activated by the outer end portions of the swivel pin in response to push button operation.

4. In a latch of the character described, a channel shaped supporting member, having an opening formed therein, a push button slidably positioned in said opening, a swivel pin pivotally mounted on the inner end of the push button, cam slots provided in the base member and engaged by the swivel pin so as to rotate said pin as it is moved by the longitudinal motion of the push button, a spring positioned to resist inward thrust of the push button, and latch bolts motivated by the swivel pin to engage and disengage latch catches.

5. In a latch of the character described, a substantially channel shaped support member having a plunger receiving opening formed in the bottom portion thereof and substantially perpendicular side portions provided with cam slots, a plunger element positioned in the opening provided therefor, a swivel pin member cooperatively linked to the plunger and movable in the cam slots to translate reciprocal motion of the plunger into gyroscopic motion of the swivel pin for the purpose of engaging and disengaging latch keepers, and a spring means engaged to the plunger element and swivel pin linkage resistive to unlatching movement thereof.

6. A latch comprising a substantially channel shaped support member, having cam ways provided therein, a push button member mounted in the support member in spaced relation to the cam ways, a swivel pin element actuated by the push button member and so mounted as to be turned about a pivot point by cam way engagement in response to push button movement, to engage and disengage latch keepers, and a spring mounted on the support member resistive to inward movement of the push button member and swivel pin.

7. In a latch of the character described, a support member having a plunger receiving opening and cam slots formed therein, a plunger element positioned in the opening provided therefor, a swivel pin member articulatedly connected to the plunger and movable in the cam slots to translate reciprocal motion of the plunger into gyroscopic motion of the swivel pin, latch bolt means articulatedly connected to said swivel pin member and spring means for resisting motion of said plunger element and swivel pin linkage.

EDWARD M. KEALY.
